UNITED STATES PATENT OFFICE.

DANIEL W. WITMER, OF SPRINGFIELD, ILLINOIS.

IMPROVEMENT IN EXPANSION-BUCKETS FOR CHAIN-PUMPS.

Specification forming part of Letters Patent No. 172,816, dated January 25, 1876; application filed July 15, 1875.

To all whom it may concern:

Be it known that I, DANIEL W. WITMER, of Springfield, in the county of Sangamon and State of Illinois, have invented a new and useful Improvement in Expansion-Buckets for Chain-Pumps; and I do hereby declare that the following is a full and exact description of the same, reference being had to the accompany drawings and to the letters of reference marked thereon.

The object of my invention is the production of an expansion-bucket for chain-pumps which shall provide simple means for dropping the water back into the well when the pump is not in use, and also furnish a simple contrivance for expanding and contracting the bucket without detaching it from the chain, and without twisting or changing in the least the tension of the chain; and my invention therein consists, principally, in the peculiar means for expanding and contracting the rubber packing; and, further, in the peculiar means for dropping the water, all as more fully hereinafter explained.

To enable others skilled in the art to manufacture my device, I now proceed to describe the same in connection with the drawings, in which—

Figure 1 is a side elevation of the bucket; Fig. 2, a central vertical section of the same; Fig. 3, a separate view of the central bolt.

Like letters denote similar parts in each figure.

A represents the central bolt, having welded on each end an eye, *a*, for attaching it to the chain, and near one end a shoulder, *a'*. This bolt has cut in its side a groove, *b*, extending its entire length through the shoulder *a'*.

B is a metallic washer slipped on the bolt *A*, and abutting against the shoulder *a'*. The washer is made large enough to turn freely upon the bolt.

C is a pipe or sleeve slipped onto the bolt nearly to the washer *B*, so as not to interfere with the turning of the washer. The sleeve is secured rigidly to the bolt by a pin, *c*, passing through the bolt and sleeve. Above the pin *c* the sleeve is screw-threaded to its end, as shown by *c'*.

D is the rubber packing, of the ordinary

construction. It is slipped over the sleeve *C*, and abuts against the washer *B*.

E is a nut, which screws on the end of the sleeve, and presses against the packing *D*. This nut is circular in outline, and smooth on its outer surface. Teeth *d* are formed on the under surface of the nut when it presses on the packing.

In using chain-pumps it is a necessity that the water should run back into the well when the pump is not in use, so as to prevent freezing. The pump-barrel also decays and wears out sooner where the water is standing in it continually. The construction of this bucket provides for dropping the water by the groove in the central bolt, which lets the water down in such a stream as not to interfere with the lifting of the water when the pump is in operation.

The operation of expanding the rubber packing of this bucket is as follows:

The link attached to the lower eye of the bucket is taken firmly in the left hand, or grasped by a wrench. The rubber packing is then taken in the right hand, and turned in the direction of the screw-thread. The teeth on the nut engage with the upper surface of the rubber packing, and by them the nut is turned. The more the packing is turned the greater is the pressure on the nut, and consequently the teeth hold tighter. The under side of the packing pressing on the loose washer causes it to turn also, thus relieving the central bolt from any tendency to twist the chain. This is done without detaching the bucket from the chain, and, as will be readily seen, without changing the tension of or twisting the chain, as in ordinary expansion-buckets.

This bucket could be constructed for the simple purpose of expanding or contracting the same, without departing from the spirit of my invention, by omitting the sleeve *C* and cutting screw-threads on one end of the central bolt, in which case the principle of expansion would be the same, but the sleeve is essential to the dropping attachment.

Having thus described my invention and some of its advantages, what I claim as new, and desire to secure by Letters Patent, is—

1. In combination, the bolt A, provided with the eyes a, the packing D, the nut E, and the loose washer B, substantially as described and shown.
2. In combination, the bolt A, provided with the eyes a, the packing D, the nut E, washer B, and sleeve C, substantially as described and shown.
3. The combination, of the bolt A, having the eyes a and groove b, the sleeve C, and the packing, substantially as described and shown.
4. The expansion-bucket for chain-pumps described, consisting of the bolt A, having

eyes a, shoulder a', and groove b, the rubber packing D, the screw-threaded sleeve C, secured to the bolt by the pin c, the loose washer B, and nut E, having the teeth d, when the several parts are constructed substantially as described and shown.

This specification signed and witnessed this 29th day of June, 1875.

DANIEL W. WITMER.
